INVENTOR.

William C. Stewart.

UNITED STATES PATENT OFFICE.

WILLIAM C. STEWART, OF SWAMPSOCKET, MASSACHUSETTS, ASSIGNOR TO UNITED SHOE MACHINERY CORPORATION, OF PATERSON, NEW JERSEY, A CORPORATION OF NEW JERSEY.

ASSEMBLING MACHINE.

Application filed March 24, 1919. Serial No. 234,581.

To all whom it may concern.

Be it known that I, WILLIAM C. STEWART, a subject of the King of Great Britain, residing at Swampscott, in the county of Essex and State of Massachusetts, have invented certain Improvements in Assembling Machines, of which the following description, in connection with the accompanying drawings, is a specification, like reference characters on the drawings indicating like parts in the several figures.

This invention relates to machines for assembling uppers of boots and shoes on their lasts preparatory to the pulling over and lasting operations. For the purpose of illustration the invention is herein shown as embodied in a machine of the type described and claimed in my prior application for Letters Patent of the United States Serial No. 191,469, filed September 14, 1917. It is to be understood, however, that the invention is not restricted to embodiment in a machine of the particular type disclosed in said application.

In the machine of my prior application above referred to, the work support is yieldingly upheld and has to be depressed by the operator as it is moved toward the machine to enable the upstanding margin of the upper at the rear end of the shoe to be positioned behind the gripper which co-operates with a wiper to tension the upper at the rear end of the shoe and wipe it into position to be secured to the heel seat. During the operation of the machine the work support is locked against depression and is also actuated rearwardly firmly to clamp the rear end of the shoe against an abutment or V-block which engages the rear end of the shoe and through which a tack is driven to fasten the upper to the last at a point adjacent to the back seam. After the operation of the machine the jack is released and is again depressible by the operator in removing the shoe. If the operator neglects to depress the shoe as he draws it away from the machine the portion of the upper wiped over the heel seat and secured by a tack is likely to catch upon the gripper jaw and be torn loose. Moreover, the rubbing of the upper at the rear end of the shoe against the abutment during the tensioning of the upper and the rearward pressure of the shoe against the abutment during the operation

of the machine are apt to mar or disfigure the upper leather where it engages the abutment, especially when delicate materials are employed.

Objects of this invention are to provide an improved construction applicable to a machine of the type above mentioned by which such disadvantages as those above indicated, among others, will be overcome.

Features of the invention consist in a novel machine organization comprising, as illustrated, means for receiving and supporting a shoe under the gripper with the upper out of contact therewith, and means for effecting relative movement of the support and gripper, for example, by a treadle mechanism, to locate the upper in operative relation to the gripper and to cause the flange of the counter to engage the gripper and be forced against the shoe bottom or heel seat. As shown herein the treadle mechanism raises the shoe to force the counter flange against the gripper which acts as a stop to limit further upward movement of the shoe. When this occurs further movement of the treadle, preferably in the same direction, causes the machine to start.

Another feature of the invention consists in a novel organization by which such relative vertical movement of the shoe support and gripper is caused to take place after operation of the machine that the shoe will be moved away from the machine without any possibility of the upper being caught on the gripper and torn loose.

A further feature of the invention consists in an improved abutment for the rear end of the shoe which is constructed and arranged to distribute the pressure when the shoe is pressed rearwardly against it, thereby avoiding marring of the shoe upper by localization of pressure at the corners of the last. As herein shown the abutment comprises a flexible band supported at its ends and arranged to engage the rear ends of the shoe including the corners and to press the upper and counter evenly to the last at this portion of the shoe.

Still another feature of the invention consists in an organization including an upper conforming band provided with an opening and means for inserting a fastening through the opening into the last.

These and other features of the invention

will appear more fully from the following description when read in connection with the accompanying drawings and will be pointed out in the appended claims.

5 In the drawings,—

Fig. 1 is a side elevation of a machine embodying this invention;

Fig. 2 is a perspective view of the work support raising and locking mechanism;

10 Fig. 3 is a perspective detail of the end abutment with one end of the band unclamped; and

Fig. 4 is a sectional plan view of parts shown in Fig. 3.

15 The numeral 2 indicates the column of the machine upon which is secured a head frame 3 in which certain instrumentalities for operating upon the shoe are mounted. These instrumentalities are operated by suitable cams on and connections to a main shaft 4 which is turned through one revolution in each cycle of the machine upon tripping of a suitable clutch with which the machine is provided and which is operated 20 by depression of a treadle lever 6 pivoted at 8 in the base of the column 2, the lever 6 being held raised by a spring 10, as shown in Fig. 1. The operating instrumentalities which are, except as hereinafter noted, 25 similar to those described in my prior application above referred to, include a gripper 12 which co-operates with a reciprocating wiper 14 to seize the upwardly extending margin of the upper at the rear of the 30 shoe, the upper being tensioned by a movement of the wiper and gripper together over the shoe bottom. The rear end of the shoe is held clamped against abutments 16 and 18 by rearward movement of the jack or 35 shoe support which is effected substantially as disclosed in my prior application. The upper is secured at the end of the shoe by tacks driven through one or both of the abutments 16 and 18 and at the heel seat the 40 upper and the counter are secured to the innersole by a tack driven through the wiper. The flange of the counter only is secured by tacks driven by tackers 22 which move over the shoe bottom with the wiper 45 and are positioned for driving tacks through the counter flange at the corners of the heel seat.

The work support comprises a member 30 pivoted to the column 2 at 32 to swing toward and from the machine, its outward movement being limited by a rod 34, as shown in Fig. 1. A hollow post 36 is arranged for vertical movement with respect to the member 30 and is guided at its lower 55 end by a stem 38 secured to the member 30 and entering the lower end of the post. A screw 40 passes through a slot in the post 36 and is threaded in the stem 38 to prevent rotation of the post and to limit its 60 longitudinal movement. Upon its upper 65

end the post 36 carries a last pin 42 upon which the last of the shoe is placed and which is swung toward the machine by movement of the support about the pivot 32. During this movement the post is in 70 lowered position, the upper end of the slot in the post 36 resting upon the screw 40 and the adjustment of the last pin 42 is such that the upwardly projecting margin of the upper at the rear of the shoe will pass beneath the gripper 12, preferably without contact therewith. After the shoe has been 75 swung into position with the upwardly projecting margin at the rear of the shoe beneath the space between the wiper 14 and 80 the gripper 12, the post 36 is raised to locate the margin of the upper behind the gripper and between the gripper and the wiper. This movement of the post 36 is effected by 85 operation of a treadle 46 which is pivoted at 48 to the forward end of the lever 6. The treadle 46 has an upwardly and rearwardly directed arm 60 which is pivoted at 62 to the lower end of an adjustable connecting rod 64, the upper end of which is 90 pivoted at 66 to a block 68 made in two parts and clamped to the post 36 by a bolt which also forms the pivot 66. The rod 64 is conveniently rendered adjustable by making it in two parts connected together by screws 95 and slots, as shown at 70 in Fig. 2. It will be seen that the arm 60 and connecting rod 64 form the links of a bent toggle which, by depression of the treadle, is partially straightened to effect upward movement of 100 the post 36. This upward movement not only positions the upstanding margin of the upper behind the gripper in position to be seized thereby but causes the inwardly projecting flange of a molded counter to engage the gripper and to be forced down into the proper position against the lining and innersole on the heel seat of the shoe. In order that suitable pressure may be exerted 105 by the gripper upon the flange of the counter, the spring 10 is made rather stiff and since it is only by overcoming the spring 10 that the machine can be tripped, the operator is obliged always to exert sufficient upward pressure on the shoe to insure that 110 the counter flange will be properly seated against the innersole before it is secured by starting of the machine. After the counter has been pressed against the gripper 12 by 115 operation of the treadle 46 and further upward movement of the shoe arrested by the gripper, sufficient additional pressure is applied to the treadle to overcome the spring 10 and effect depression of the lever 6 to 120 start the machine, the upward pressure on the last being maintained and, in fact, increased during the tripping operation by 125 further straightening of the toggle 60, 64. When the machine starts a hook 76 drops behind a roll 72 on the member 30, draws the 130

shoe support toward the machine to clamp the rear end of the shoe against the abutments 16, 18, and causes a pawl 74 to engage teeth formed on the post 36 and lock the post in raised position. This locking mechanism is similar to that disclosed in United States Letters Patent No. 1,356,510 granted October 26, 1920, upon an application of Orrell Ashton, to which reference 10 may be had for a complete description thereof and, therefore, need not be further explained herein.

The upper abutment 16 is formed as shown in Figs. 3 and 4. The forward end of the abutment member 16 is provided with two prongs 82, 84, and between the prongs the member is cut away to form a recess 86 for the rear end of the shoe. Extending from one prong to the other across the recess 86 20 is a band 88 of suitable material, for example, a strong fabric. The ends of the band are passed around the ends of the prongs and secured by clamping members 90, 92. On the outer sides of the prongs 82, 84 are projections 94, 96 over which the ends of the band are positioned and the clamping members 90, 92 are provided with flanges 98, 100 which engage the band, one on each side of each projection 94, 96. Screws 102 pass through 30 the clamping members and are threaded into the prongs 82, 84 to secure the clamping members in clamping position against the band. At one side of the center of the band is an opening 104 behind which one of the 35 rear tackers 106, with which the machine is provided, is located. In the operation of the machine a tack is driven through the opening 104 to secure the upper to the rear end of the last and a similar tacker drives a tack 40 through the lower abutment 18. The machine is so organized that the lower tack is driven immediately after the shoe is clamped in the machine, and the upper tack is driven after the upper has been drawn upwardly by 45 the gripper and wiped over the shoe bottom. During the upward tensioning of the upper there is more or less rubbing of the upper across the face of the upper abutment, and one important function of the fabric band 88 50 is to prevent marring of the upper such as is apt to occur when delicate upper stock is forcibly rubbed against a metallic surface. Moreover, when the shoe is forced rearwardly into the machine by the action of the hook 55 76, the band 88 distributes the pressure and causes the counter to be forced into conformity with the shape of the rear end of the last. This action also prevents localization 60 of the pressure upon the corners of the last such as occurs when the abutment has the V-shape disclosed in the construction of my prior application above referred to, and hence the danger that such localized pressure 65 will produce a mark or blemish upon delicate upper material is avoided.

After the machine has been set in operation by full depression of the treadle the operator's foot is removed from the treadle, the machine going through its cycle and stopping. Before the machine stops the hook 76 is, of course, raised and hence the pawl 74 is released from holding relation to the teeth on the post 36, causing the post 36 to drop by gravity. Therefore, when the shoe is withdrawn from the machine by outward swinging 75 movement of the post 36, the secured portion of the upper at the rear of the heel seat is entirely below the gripper 12 and any possibility of its catching on the gripper as the shoe is withdrawn is avoided. 80

Having thus described my invention, what I claim as new and desire to secure by Letters Patent of the United States is:

1. In a machine for assembling parts of boots and shoes upon a last preliminary to lasting, the combination of a gripper, a work support normally sufficiently below the gripper to provide for positioning a shoe in line with the gripper opening without interference of the gripper with the shoe upper, 85 means for then effecting relative movement of the gripper and work support to carry the work into operative relation to the gripper, and means for securing the upper in assembled relation. 90

2. In a machine for assembling parts of boots and shoes upon a last preliminary to lasting, the combination of a gripper, a work support movable toward and from the machine in a plane sufficiently below the gripper 100 to provide for positioning a shoe below the gripper with the upper in line with the gripper opening, means for then effecting relative movement of the gripper and work support to position the upper in the gripper 105 opening, and means for operating the gripper and securing the upper in assembled relation upon the last. 110

3. In a machine for assembling parts of boots and shoes in proper relation upon a last preliminary to lasting, the combination of a gripper, a work support movable toward and from the gripper in a plane sufficiently below the gripper to allow the upper to pass beneath the gripper, means for then effecting 115 relative movement of the support and gripper to cause the upper to be positioned behind the gripper and to cause the flange of the counter to be pressed by the gripper upon the heel seat, and means for securing the 120 upper. 125

4. In a machine for assembling parts of boots and shoes in proper relation upon a last preliminary to lasting, the combination of a work support movable toward and from the machine, a gripper, means for securing the upper to the last, and means for effecting relative movement of separation 130 between the support and gripper vertically after the securing operation and prior to 135

- movement of the support from the machine so that the shoe will be withdrawn from the machine without contact of the gripper with the secured upper.
5. In a machine for assembling parts of boots and shoes in proper relation upon a last preliminary to lasting, the combination of a work support, movable into and out of operative relation to the machine, a gripper, means for effecting relative movement of the support and gripper to cause the upper to be positioned behind the gripper and to cause the flange of the counter to be pressed by the gripper upon the heel seat, 75 means for securing the upper, and means for effecting relative movement of separation of the support and gripper after the securing operation and prior to movement of the support out of operative relation to the machine to allow the secured upper to pass the gripper out of contact therewith when the shoe is removed from the machine.
6. In a machine of the class described, the combination of a reciprocating wiper, a gripper adapted to co-operate with the wiper in seizing the upstanding margin of the upper of a shoe, a shoe support movable toward the machine substantially in a horizontal plane to cause passage of the upper beneath the gripper, means for raising the support to position the upper behind the gripper, means for operating the gripper and wiper, and means for securing the upper.
35. 7. In a machine of the class described, the combination of a reciprocating wiper, a gripper adapted to co-operate with the wiper in seizing the upstanding margin of the upper of a shoe, a shoe support movable toward the machine in a plane to cause passage of the upper beneath the gripper, means for raising the support to position the upper behind the gripper and to force the counter flange against the gripper, and 100 means operated as a result of pressure of the shoe against the gripper to start the machine.
8. In a machine of the class described, the combination of a reciprocating wiper, upper securing means, a shoe support, means for raising the shoe support, a stop to limit upward movement of the shoe, and means effective when the shoe reaches the stop to start the machine.
55. 9. In a machine of the class described, the combination of a reciprocating wiper, upper securing means, a shoe support, means for raising the shoe support, a stop, means for raising the support to force the shoe 115 against the stop, said means comprising a bent toggle operating when partially straightened to force the shoe against the stop, and means operated by further straightening movement of the toggle to start the machine.
10. In a machine for assembling parts of boots and shoes in proper relation upon their lasts preliminary to lasting, the combination of a gripper, a work support movable in a plane below the gripper to cause the upstanding margin of the upper to be positioned at the rear of the gripper, means for raising the support against gravity to cause the upper to be positioned behind the gripper and to force the flange of the counter against the gripper, a wiper, means for operating the gripper and wiper relatively to seize the upper, means for operating the wiper and gripper together to lay the upper over the heel seat, means for locking the support against vertical movement, means for securing the overlaid upper, and means for unlocking the support to permit separation of the shoe and gripper during the removal of the shoe from the machine. 120
11. In a machine for securing parts of boots and shoes in assembled relation on a last preparatory to lasting, the combination of means for working an upper over the bottom of the last, a shoe support movable toward and from the overworking means and having a depressed position during its movement toward the overworking means to cause the upwardly projecting margin of the upper at the rear end of the shoe to pass beneath the overworking means during movement of the support toward it, means for raising the support to position the upper margin in operative relation to the overworking means, means for locking the support in raised position and releasing the support after the operation of the machine on the shoe, and means for operating the overworking means and for securing the upper to the last in assembled relation. 125
12. In a machine of the class described, the combination of instrumentalities for conforming the upper to the rear end of the last and securing the upper in assembled relation, a shoe support movable toward and from the said instrumentalities and also movable vertically, manually operable means for raising the support, said means being arranged upon further movement to start the machine, and means operating after the machine starts to lock the shoe support to hold the shoe in operative relation to the upper conforming instrumentalities and to unlock the jack after the operation of said instrumentalities to allow the jack to descend. 130
13. In a machine of the class described, the combination of a gripper for tensioning the upper at the rear end of the last, means for securing the upper in assembled relation, a shoe support movable toward and from the gripper and also movable vertically, manually operable means for raising the support, said means being arranged upon further movement to start the machine to effect the tensioning and securing operation, and 135

- means operating after the machine starts to lock the shoe support to hold the shoe in operative relation to the gripper and securing means and to unlock the jack after the operation of said gripper and securing means to allow the jack to descend out of the way of the gripper during movement of the support away from the gripper. 65
14. In a machine of the class described, the combination of instrumentalities for conforming the upper to the rear end of the last including a gripper for tensioning the upper at the rear end of the last, means for securing the upper in assembled relation, a shoe support movable toward and from said instrumentalities and also movable vertically, manually operable means for raising the support to bring the shoe upper into operative relation to the gripper, said means being arranged upon further movement to start the machine, and means operating after the machine starts to lock the shoe support to hold the shoe in operative relation to the upper conforming instrumentalities and to unlock the jack after the operation of said instrumentalities and said securing means to allow the jack to descend and move the shoe out of the way of the gripper when the support is moved away from the machine. 70
15. In a machine for securing parts of boots and shoes in assembled relation on a last preparatory to lasting, the combination of a gripper, a shoe support movable toward and from the gripper and having a depressed normal position to allow the upwardly projecting margin of the upper at the rear end of the shoe to pass beneath the gripper during movement of the support toward the gripper, manual means for raising the support to position the upper margin behind the gripper and for starting the machine, power means for locking the support in raised position, and means for operating the gripper, securing the upper to the last in assembled relation, and releasing the support after the operation of the machine on the shoe. 75
16. In a machine for securing parts of boots and shoes in assembled relation on a last preparatory to lasting, the combination of a gripper, a shoe support movable toward and from the gripper and having a depressed normal position to allow the upwardly projecting margin of the upper at the rear end of the shoe to pass beneath the gripper during movement of the support toward the gripper, manual means operable after the shoe is positioned beneath the gripper for raising the support to position the upper margin behind the gripper and operable further to start the machine, power means for locking the support in raised position, and means for operating the gripper, for securing the upper to the last in assembled relation, and releasing the support after the operation of the machine on the shoe. 80
17. In a machine of the class described, a pronged block against which the rear end of the shoe is held to receive fastenings in the rear end thereof, the block having projections on the outer sides of its prongs, a flexible band extending loosely across the shoe receiving space between the prongs and having its ends disposed over the projections on outer faces of the prongs, clamping members, and means for securing the clamping members to hold the band against the projections on the prongs. 85
18. In a machine of the class described, a pronged block against which the rear end of the shoe is held to receive fastenings in the rear end thereof, the block having projections on the outer sides of its prongs, a flexible band extending loosely across the shoe receiving space between the prongs and having its ends disposed over the projections on the outer faces of the prongs, clamping members having clamping jaws arranged on each side of each projection, and means for holding the clamping members against the prongs. 90
19. In a machine of the class described, a V-member against which the rear end of the shoe is held to receive fastenings in the rear end thereof, the V-member having projections on its outer sides and being cut away in the center of its shoe receiving portion, a flexible band extending loosely across the shoe receiving space of the V-member and having its ends disposed over the projections on the outer sides of the member, said band being spaced from the cut away portion, and means for clamping the band against the projections. 95
20. A machine of the class described having, in combination, means for securing the upper in assembled relation, an abutment, means for pressing the shoe against the abutment during the securing operations, and a flexible cover for the abutment arranged out of contact with the abutment except at its ends to prevent marring of the upper leather by the pressure of the shoe against the abutment during the securing operation. 100
21. A machine of the class described having, in combination, a gripper for tensioning the upper at the rear end of the shoe, means for securing the upper in assembled relation, an abutment against which the shoe is clamped during the tensioning and securing operations, and a flexible cover for the abutment engaging the abutment only at its ends to prevent marring of the upper leather by rubbing of the upper across the abutment during the tensioning and clamping operations. 105
22. In a machine of the class described, 110
- 115
- 120
- 125

the combination of a flexible band for conforming an upper to its last at the end of a shoe, said band having an opening adjacent to the end of the shoe, and means for inserting a fastening through the band into the end of the last.

23. In a machine of the class described, the combination of a band supported at its ends and free to assume the contour of a last for conforming an upper and counter to the last at the rear end of a shoe, said band having an opening adjacent to the back seam of the shoe, and means for inserting a fastening through the opening of the band into the rear end of the last adjacent to the back seam.

24. In a machine for assembling parts of boots and shoes on a last preparatory to lasting, the combination of two abutments arranged one above the other to be engaged by the rear end of a shoe, means for clamping and securing the upper to the last adjacent to the lower abutment, means for tensioning the upper across the shoe engaging end of the upper abutment and securing it to the heel seat, and a flexible member extending across the upper abutment to prevent marring of the upper during movement of the upper across it in the tensioning operation.

25. In a machine of the class described, the combination of a pronged abutment, a work support movable toward and from the abutment, means for forcing the support against the abutment, means for inserting fastenings into the last through the abutment, and a flexible strip extending freely across the abutment between the prongs and acting to force the upper against the last at the rear of the last where the fastenings are driven.

26. In a machine of the class described, the combination of means for operating upon an upper to which the upper is presented in upstanding relation to the sole, a shoe support movable horizontally and vertically relatively to the operating means, means for locking the support against vertical movement after the machine starts, and means operating as an incident to one of said support movements to start the machine.

27. In a machine of the class described, the combination of means for operating upon an upper to which the upper is presented in upstanding relation to the sole, a shoe support movable horizontally and vertically relatively to the operating means, means for locking the support against vertical movement after the machine starts, and means operating as an incident to upward vertical movement of the support to start the machine.

28. In a machine of the class described, means for operating on a shoe, a shoe support movable vertically to present the shoe

in proper relation to the operating means, a stop to limit upward movement of the shoe, manual means for raising the shoe, and means operated by continued movement of the manual means after the shoe is arrested for starting the machine.

29. In a machine of the class described, means for operating on a shoe, a shoe support movable vertically to present the shoe in proper relation to the operating means, a stop to limit upward movement of the shoe, a treadle for raising the shoe support, and means operable by movement of the treadle after movement of the shoe is arrested for starting the machine.

30. In a machine of the class described, the combination of means for working an upper over a last, a shoe support movable vertically to present the upper to the overworking means, means for limiting movement of the shoe when the upper is in proper relation to the overworking means, means for raising the shoe support, and means becoming operative when movement of the shoe is arrested for starting the machine.

31. In a machine of the class described, the combination of means for operating upon an upper to which the upper is presented in upstanding relation to the sole, a shoe support movable vertically to bring the shoe into engagement with the operating means by which its further movement is resisted, means for locking the support against vertical movement after the machine starts, and means becoming operative as a result of resistance to further upward movement of the support to start the machine.

32. In a machine of the class described, the combination of means for seizing an upper to which the upper is presented in upstanding relation to the sole, a shoe support movable horizontally and vertically relatively to the seizing means, means for locking the support against movement after the machine starts, and means operating as a result of upward vertical pressure of the support against the seizing means to start the machine and cause the upper to be seized.

33. In a machine of the class described, means for operating on a shoe, a shoe support, a stop to arrest the shoe between which and the support there is relative movement vertically to present the shoe in proper relation to the operating means, manual means for effecting relative movement of the shoe support and stop, and means operated by continued movement of the manual means after the shoe is arrested for starting the machine.

34. In a machine of the class described, the combination of means for operating upon the upper including a wiper and a gripper between which the upper is presented in upstanding relation to the sole, a shoe support movable horizontally into position

- below the operating means and then vertically relatively to the operating means to position the upper between the wiper and gripper, means for locking the support against 5 vertical movement after the machine starts, and means operating as an incident to vertical upward pressure of the support to start the machine.
35. In a machine of the class described, 10 the combination of means for seizing and updrawing and overlaying an upper to which means the upper is presented in upstanding relation to the sole, a shoe support movable horizontally and vertically relatively to the operating means, means for locking the support against downward vertical movement and against outward movement after the machine starts, means for raising the support, and means operating 15 as a result of upward vertical pressure of the support to start the machine.
36. In a machine of the class described, a wiper for wiping in the upper at the end of a shoe, a shoe support movable to present 20 the shoe in proper relation to the wiper, means for raising the shoe toward the wiper, and means operated by movement of the shoe support for starting the machine.
37. In a machine of the class described, 25 the combination of a reciprocating wiper, upper securing means, a shoe support movable vertically to present the shoe in proper relation to the wiper, means to limit upward movement of the shoe when it is in proper 30 relation to the wiper, a treadle for raising the shoe support, and means operated by further movement of the treadle after movement of the shoe is arrested for starting the machine.
40. 38. In a machine of the class described, 35 the combination of a wiper for working an upper over a last, means for securing the upper in overworked position, a shoe support movable vertically to present the upper 40 to the wiper, means for limiting movement of the shoe with the upper in proper relation to the wiper, means for raising the shoe support, and means becoming operative when movement of the shoe is arrested for starting 45 the machine.
39. In a machine of the class described, 50 means for operating on a shoe upper by fold-
- ing in the upstanding margin of the upper upon the flange of the counter, a stop to engage the counter flange inside the upstanding upper, a shoe support movable vertically to present the flange against the stop and the upper in proper relation to the operating means, a treadle for raising the shoe support to seat the counter flange against the heel seat, and means operated by further movement of the treadle after the counter has been seated for starting the machine. 55
40. In a machine of the class described, 60 the combination of means for working an upper over the heel seat of a shoe, a shoe support movable vertically to present the upper to the overworking means, means engaging the flange of the counter inside the upper and limiting movement of the shoe 65 when the upper is in proper relation to the overworking means, and manually operated means for raising the shoe support to cause the flange of the counter to be pressed into place. 70
41. In a machine of the class described, 75 the combination of means for working an upper over the heel seat of a shoe, a shoe support movable vertically to present the upper to the overworking means, means engaging the flange of the counter inside the upper and limiting movement of the shoe when the upper is in proper relation to the overworking means, and manually operated means for raising the shoe support to cause 80 the flange of the counter to be pressed into place, said means becoming effective when further movement of the shoe is resisted to start the machine. 85
42. In a machine of the class described, 90 the combination of means for operating upon the upper including a wiper and a gripper to which the upper is presented in upstanding relation to the sole, a shoe support movable horizontally and vertically to position the upper for the action of the wiper and gripper, means for locking the support against vertical movement after the machine starts, and means operating as an incident to a positioning movement of the support to 95 start the machine. 100

In testimony whereof I have signed my name to this specification.

WILLIAM C. STEWART.
